ORTHODONTIC CRADLEBOARD

Hal A. Huggins, 100 E. Cheyenne Road,
Colorado Springs, Colo. 80906

Filed July 6, 1971, Ser. No. 160,248

Term of patent 14 years

Int. Cl. D24—01; D6—01
U.S. Cl. D24—1 B

Fig. 1 Fig. 2

Fig. 3

Fig. 5Fig. 4

FIG. 1 is a top plan view of the orthodontic cradleboard showing my new design;

FIG. 2 is a side view of the orthodontic cradleboard;

FIG. 3 is an end view of one end of the orthodontic cradleboard showing my design;

FIG. 4 is an end view of the other end of the orthodontic cradleboard showing my design; and

FIG. 5 is a bottom view of the orthodontic cradleboard showing my design.

The side of the orthodontic cradleboard not shown is a mirror image of the side shown in FIG. 2.

I claim:

The ornamental design for an orthodontic cradleboard, as shown and described.
